United States Patent Office

Des. 185,584
Patented June 23, 1959

185,584

CHAIR

Norman Steuer, San Rafael, Calif.

Application December 9, 1958, Serial No. 53,707

Term of patent 14 years

(Cl. D15—1)

FIG. 1

FIG. 2

FIG. 3

FIG. 4

Figure 1 is a front three-quarters perspective view of a chair showing my new design;

Figure 2 is a rear three-quarters perspective view thereof;

Figure 3 is a side elevational view; and

Figure 4 is a top view.

I claim:

The ornamental design for a chair, as shown.
